ODIE OSON COLLINS, OF RIVERSIDE, CALIFORNIA

GRIPPING DEVICE

Application filed July 15, 1929. Serial No. 378,518.

This invention relates to gripping devices of the type employed for use in connection with wire stretchers, and for other uses.

An object of the invention is the provision of an improved gripping device of the general class described, which is provided with means for facilitating removal of the gripping device from the member gripped.

Another object is the provision of improvements in gripping devices of the general class described, which do not add to the cost of production thereof, but materially increase the efficiency of the device to which my invention has been adapted.

15 The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is a side elevation of a gripping device incorporating the principles of the present invention, with the direction of view indicated by the arrow 1 of Fig. 1;

Fig. 2 is a bottom plan view, the direction of view being indicated by the arrow 2 of Fig. 1;

30 Fig. 3 is a side elevation with the direction of view indicated by the arrow 3 of Fig. 2. Portions of the figure are broken away to better disclose operating parts of the device;

Fig. 4 is a fragmentary, horizontal sectional view taken upon the line 4—4 of Fig. 1;

35 Fig. 5 is a highly enlarged vertical sectional view taken through the gripping jaws of the device when in gripping position upon a wire, showing the indentation made in the wire by the jaws when firmly engaged thereupon. Portions are broken away to reduce the length of the figure.

This invention constitutes improvements in gripping devices employed for imposing tension upon such members as wires, either insulated or bare; and more especially constitutes improvements in the wire clamp forming the subject matter of Patent No. 800,745 issued October 3, 1905, to John M. Klein.

50 This wire clamp and others to which the

principles of the present invention are applicable, comprise a pair of jaws at least one of which is movable, and is provided with activating means for pressing it toward the other jaw, with a relatively great mechanical advantage, this clamping movement of the jaws being caused by a force which is a component force developed from the actual pull exerted against the clamp in imposing tension upon the member gripped by the clamp. In fact, so great is the gripping action of the jaws under such circumstances, that from it arises the inherent disadvantage of such gripping devices, inasmuch as the extreme pressure exerted by the jaws upon the wire, causes the jaws to actually form a depression in the wire within which the jaws become seated, and having an abrupt shoulder at each end of the depression, against which the associated ends of the jaws engage. These gripping devices when being released, necessitate at least a slight degree of longitudinal movement of one jaw in respect to the other—i. e., at least one of the jaws must move longitudinally of the member gripped; and due to the presence of the shoulder at that end of the depression toward which the jaw must move in being released, extreme difficulty is very frequently encountered in releasing the gripping member from the tensioned member. This is especially true when the device is employed upon insulated wire, because the insulation conventionally employed, is relatively soft as compared to metallic wire. However, the same condition prevails, but to a lesser extent when bare wire is being stretched. Under certain circumstances of use, so firmly do the jaws become engaged within the recess formed in this manner, that it is necessary to use considerable force in their disengagement. This is ordinarily accomplished by hammering the movable jaw or the stationary jaw upon the end thereof opposite that toward which the longitudinal movement must occur, thus shearing off the shoulder formed in the wire and past which the jaw must be forced. Obviously, this not only causes considerable inconvenience and delay, but it is also harmful to the gripping device.

The drawings disclose a gripping device operated upon the principles above outlined. It comprises a body portion 6 upon the after end 7 of which a rigid jaw 8 is carried. A movable jaw 9 is cooperatively opposed to the rigid jaw 8, and is connected to the body portion 6 through the expedient of a rivet 11 or other suitable pin preferably rigid with a web 12 extending upwards from the movable jaw 9.

10 The rivet 11 extends slidably through an arcuate slot 13 in the body portion 6, being provided with a head 14 upon the opposite side of the body 6, to prevent displacement thereof.

15 A lever 16 is pivoted to the after end 7 of the body portion 6, as by a rivet 17, and extends therefrom transversely of the jaws 8 and 9, to be coupled at its free end to suitable draft means such as a clevis 18, through the 20 expedient of links 19. A suitable pin 21 pivotally unites one end of each link 19 to the outer end of the lever 16; and another pin 22 pivotally connects the other end of each link 19 to the clevis 18. The links 19 are disposed angularly in respect to the body 6, so that the pin 22 may be accommodated within a slot 23 preferably inclined slightly, and formed within the body 6, the free end of the lever 16, being at some distance beyond the upper edge of the body 6. As a result of this arrangement of the parts, any force exerted upon the clevis 18, causing it to move toward the right as viewed upon Figs. 1, 2, and 3, will not only cause the entire gripping device to move in the same direction with equal force, but it will also cause the lever 16 to be swung about the pivot 17 in a clockwise direction, as viewed upon Fig. 1.

35 The movable jaw 9 is pivotally attached to the lever 16 by means of a pin 26 carried by the lever 16 and extending through an aperture 27 in the web 12 of the movable jaw 9. In gripping devices heretofore employed, the pin 26 while being movable in rotary motion within the aperture 27, fits nicely therein, eliminating the possibility of any play between the lever 16 and jaw 9. Furthermore, 40 the distance between centers of the pins 17 and 26, is equal to the radius of the arc of the slot 13; with the result that when the lever 16 is pivoted about the pin 17, the resultant movement of the jaw 9, caused by engagement of the pin 26 within the aperture 27, and engagement of the pin 11 within the slot 13, is translatory movement, wherein the jaw 9 remains parallel to the stationary jaw 8, and moves both longitudinally thereof and either toward or away therefrom, depending upon the direction of pivotal movement of the lever 16.

45 A spring 31 is coiled about a pin 32 extending between the two links 19, and has one end 33 bearing against a pin 34 rigid with one of

the links 19, and its other end 36 bearing against a shoulder 37 upon the forward edge of the lever 16. The action of the spring 31 results in the imposition of a slight degree of spring tension upon the lever 16, in that direction which causes the jaw 9 to be moved toward the jaw 8, the purpose being to impose at least a slight degree of compression upon the wire 38 or other member to be tensioned, before any pull is exerted upon the clevis 18, and thus avoid slippage of the device in respect to the wire 38 when tension is initially exerted upon the clevis.

50 The device thus far described, constitutes a well known type of wire clamp. Its operation depends upon the longitudinal and clamping movement of one jaw 9 in respect to the other when the lever 16 is pivoted forward, by imposing tension upon the links 19 from the clevis. It is obvious that when a wire 38 is engaged between the jaws 8 and 9, and then the clevis 18 pulled forward, the lever 16 will be pivoted forward, carrying the jaw 9 forward in arcuate movement, wherein it moves both longitudinally in respect to the wire, and toward the jaw 8. This movement of the jaw 9 will continue until it presses against the wire 38 firmly enough to overcome the extremely great mechanical advantage developed through the lever 16, and which results in a clamping force several times greater than the force exerted against the clevis 18. As a result of this very heavy clamping force, the jaws 8 and 9 have the tendency to become actually embedded within the wire 38, as indicated upon Fig. 5. Thus a portion 41 of reduced diameter, is formed in the wire 38, this portion 41 corresponding in length to the jaws 8 and 9, and terminating in shoulders 42 and 43. Therefore, when it is desired to remove the clamp from the wire 38, tension upon the clevis 18 having first been removed, difficulty is frequently encountered because of the presence of the shoulder 43 against which the associated end of the movable jaw 9 engages. Separation of the jaws is effected by reverse movement of the lever 16, which causes translatory movement of the jaw 9 in an arc in which the jaw 9 again moves longitudinally of the wire 38, but away from the fixed jaw 8. The presence of the shoulder 43 obviously makes the initial longitudinal movement of the jaw very difficult, inasmuch as the actual metal must be sheared if a bare wire is gripped, or the insulation must be cut away by the leading edge of the jaw 9 if an insulated wire is gripped.

55 The present invention contemplates improving the device hereinabove described, with especial reference to the means of interconnecting the lever 16 to the web 12 of the movable jaw 9. My invention comprises enlarging the aperture 27 preferably in a direction measured substantially longitudinally of

the jaws. In the present form of the device therefore, the width of the aperture 46, measured in a direction perpendicular to the jaws 8 and 9, substantially coincides with the diameter of the pin 26; whereas the major axis of the aperture 46, which is disposed substantially perpendicular to this width, is materially greater than the diameter of the pin 26.

As a result of my improvement, initial releasing movement of the lever 16, will cause the after end of the movable jaw 9—i. e., that end of the jaw 9 remote from the clevis 18, to be forced directly away from the jaw 8 and wire 38, because of the engagement of the pin 26 against the upper edge of the aperture 27. However, longitudinal movement of the jaw 9 is not caused by the initial movement of the lever 16, inasmuch as the pin 26 must move to the after edge of the elongated aperture 27, before such longitudinal movement of the jaw 9 commences. Obviously, by this time, the shoulder of the jaw 9, will have been removed from the shoulder 43 which it has formed within the wire 38; with the result that continued releasing movement of the lever 16 may be effected without difficulty, because of the removal of the jaw 9 from that position in which it encounters the shoulder 43 before longitudinal movement of the jaw is commenced.

It is to be understood that the details of the invention as herein disclosed, are subject to alteration within the spirit or scope 35 of the appended claims.

I claim:

1. In a gripping device, a pair of jaws movable relatively to each other, actuating means associated with said jaws, and means 40 operable by said actuating means for initially moving one of said jaws perpendicularly and subsequently in arcuate motion away from the other jaw.

2. In a gripping device, a pair of jaws 45 movable relatively of each other, actuating means associated with said jaws, and means operable by said actuating means for initially drawing one end of one jaw perpendicularly away from the other jaw and subsequently 50 moving the entire first mentioned jaw obliquely away from said other jaw.

3. In a gripping device, a pair of jaws mounted for adjustment relatively of each other, a lever extending transversely of said 55 jaws, a pin pivotally joining each jaw to said lever, each pin being disposed within an aperture in said lever and in another aperture in the associated jaw, the pin associated with one of said jaws being materially smaller 60 than one of the apertures within which it is seated.

4. A gripping device comprising a body portion, a rigid jaw and an opposed movable jaw carried thereby, a lever extending trans- 65 versely of said jaws and pivoted to said body

portion, a pivot pin carried by said lever beyond the jaws from its point of attachment to the body portion, said pin seating within an aperture within the movable jaw and larger than the pin, and draft means 70 coupled to said lever beyond said pin.

5. A gripping device comprising a body portion, a rigid jaw and an opposed movable jaw carried thereby, a lever extending transversely of said jaws and pivoted to said body portion, a pivot pin carried by said lever beyond the jaws from its point of attachment to the body portion, said pin seating within an aperture within the movable jaw, said aperture fitting the pin in respect to 80 width measured in a direction transverse to the jaws and being elongated in a direction perpendicular to said width, and draft means coupled to said lever beyond said pin.

6. A gripping device comprising a body portion, a rigid jaw and an opposed movable jaw carried thereby, a lever extending transversely of said jaws and pivoted to said body portion, a pivot pin carried by said lever beyond the jaws from its point of attachment to the body portion, said pin seating within an aperture within the movable jaw, said aperture being elongated to a greater length than the diameter of the pin, the major axis of the aperture extending substantially parallel to the jaws, and draft means 90 coupled to said lever beyond said pin.

7. In a gripping device, a pair of jaws mounted for adjustment relatively of each other, a lever extending transversely of said 100 jaws, a pin pivotally joining each jaw to said lever, each pin being disposed within an aperture in said lever and in another aperture in the associated jaw, said lever being disposed angularly with respect to the gripping faces of said jaws when in gripping position, and the pin associated with one of said jaws being materially smaller than one of the apertures within which it is seated.

8. A gripping device comprising a body portion, a rigid jaw and an opposed movable jaw carried thereby, a lever extending transversely of said jaws and pivoted to said body portion, a pivot pin carried by said lever beyond the jaws from its point of attachment to the body portion, said pin seating within an aperture within the movable jaw, said aperture fitting the pin in respect to width measured in a direction transverse to the jaws and being elongated in a direction 110 perpendicular to said width, means limiting the motion of said movable jaw in respect to the fixed jaw substantially to translatory motion, and draft means coupled to said lever beyond said pin.

9. A gripping device comprising a body portion, a rigid jaw and an opposed movable jaw carried thereby, a lever extending transversely of said jaws and pivoted to said body portion, a pivot pin carried by said lever 120

beyond the jaws from its point of attachment to the body portion, said pin seating within an aperture within the movable jaw, said aperture being elongated to a greater length than the diameter of the pin, the major axis of the aperture extending substantially parallel to the jaws, means limiting the motion of said movable jaw in respect to the fixed jaw substantially to translatory motion, and draft means coupled to said lever beyond said pin.

10. In a gripping device, a pair of jaws mounted for adjustment relatively of each other, a lever extending transversely of said jaws, a pin pivotally joining each jaw to said lever, each pin being disposed within an aperture in said lever and in another aperture in the associated jaw, said lever being disposed angularly with respect to the gripping faces of said jaws when in gripping position, and one of said apertures being materially relieved in a direction parallel to said gripping faces whereby initial retracting movement of said lever occurs without causing longitudinal movement of the associated jaw.

In testimony whereof I have signed my name to this specification.

ODIE OSON COLLINS.
